FASTENER-APPLYING IMPLEMENT

Charles M. Lindstrom, Westerly, R. I., assignor
to Boston Wire Stitcher Company, Stonington,
Conn., a corporation of Maine

Original application March 29, 1945, Serial No.
585,486. Divided and this application January
31, 1947, Serial No. 725,522

6 Claims. (Cl. 1-49)

1

This invention relates to improvements in fastener-applying implements and the present application is a division of my prior application for United States Letters Patent Serial No. 585,486, filed March 29, 1945.

One object of the present invention is to provide an implement of the type indicated comprising improved fastener-feeding and driving means for preventing the driving of a second fastener before the first one has been discharged from the implement.

Another object is to provide an implement of the type indicated having a magazine in which the fasteners are fed forwardly and the foremost one in the series first carried down onto a rest in reserve position before it is applied to the work at the next operation of the fastener-applying means.

Another object is to provide an implement for applying fasteners of a type having crowned heads or crossbars by first flattening their heads and thereafter driving them into the work and clinching their legs on the under side thereof with close contact of the parts of the fasteners against the work.

Another object is to provide an implement of the type indicated in which the crowned head or crossbar of the fastener is flattened by the driver as the fastener is carried down into reserve position on a rest and the legs of the fastener are spread apart so that the ends of the crossbar underlie hold-down or retaining means to prevent the fastener from rising up.

Further objects of the improvement are set forth in the following specification which describes a preferred form of construction of the invention, by way of example, as illustrated by the accompanying drawings. In the drawings:

Fig. 1 is a sectional view of the implement taken in a vertical plane coincident with its longitudinal axis and showing the operating parts within its interior;

Fig. 2 is a plan view of the implement with the fastener-applying arm shown in transverse section to illustrate the parts enclosed therein;

Fig. 3 is an enlarged transverse part-sectional view of the forward part of the implement taken on line 3-3 of Fig. 1;

Fig. 4 is a similarly enlarged longitudinal sectional view of the forepart of the implement showing the parts in the same position as in Fig. 3;

Fig. 5 is an enlarged sectional view similar to Fig. 3 but showing the parts of the implement in position with the fastener-applying means depressed toward the clinching means;

Fig. 6 is an enlarged longitudinal sectional view of the forepart of the implement showing its operating parts in the same position as in Fig. 5;

Fig. 7 is a view similar to Fig. 3 showing the

2

fastener-applying means as elevated in position just prior to driving a staple into the work;

Fig. 8 is a longitudinal sectional view of the forepart of the implement showing the parts in the same position as in Fig. 7;

Fig. 9 is a detailed view illustrating the relationship between the fastener and its driving means just prior to flattening its crowned crossbar; and

Fig. 10 shows the driving means depressed to straighten or flatten the crossbar of a fastener while spreading its legs to position the fastener beneath the hold-down means.

The present improvements are shown in substantially the same form as in my prior application from which this application is divided and only such parts as are necessary to an understanding of the fastener-applying means will be described in detail herein. In general, the implement comprises a magazine 2 in the form of a trough-shaped arm, a fastener-applying arm 3 pivotally connected to the magazine-arm in overlying relation thereto, a clinching arm 4 underlying the magazine-arm and pivoted thereto, and a manually-operable force-multiplying lever 5 connected to actuate the fastener-applying means and clincher-arm.

The magazine 2 is of channel-shape in cross-section comprising a bottom wall 8 and parallel side walls 9 extending upwardly therefrom as shown in Figs. 1, 2 and 3. The forward ends of the side walls 9 of the magazine project beyond its bottom wall 8 and are folded inwardly in flange-like portions 10, see Figs. 1 and 2. At the forward end of the magazine 2 the side walls 9 are extended upwardly in wing-like portions 12 formed with outwardly-projecting ears 13 bent at right-angles to provide abutments employed as stops to limit the relative movement between the magazine 2 and the arm 3 as later explained. Mounted within the magazine-arm 2 and extending longitudinally thereof is a staple-support or core 15 across which U-shaped staples 8 may be straddled to be fed therewith for delivery to the applying means. The staple-core 15 is of U-shape or channel-form in cross-section having a bottom wall 16 and upstanding side walls 17, see Fig. 3, with flanges 18, shown in Fig. 4, at the top of the side walls folded inwardly toward each other. In the present form of construction of the implement the side flanges 18 are relatively narrow throughout the greater portion of the length of the core 15, but adjacent the forward end they are extended in opposite angular relationship to meet substantially at the center, see dotted lines in Fig. 3, in rectangularly-shaped portions or tabs 20. These meeting portions or tabs 20 are inclined upwardly toward the center of the core to provide a beveled rest for staples 8 having crowned heads or crossbars. In other

55

cases the rest formed by the tab portions 20 may take different shapes, for example, they may have a curved contour for an arcuate form of the staple crowns.

The forward end of the core 15 is spaced a slight distance rearwardly of the inwardly-folded flanges 10 at the front of the magazine-arm 2 to provide vertical guide-ways or grooves 21 adapted to receive a slidable staple-driver 25, to be described later. Overlying the top of the core 15 at its forward end in spaced relation to the tabs 20 is a substantially U-shaped guard-member 22 having its sides welded or otherwise suitably secured to the upstanding wing-like portions 12 on the sides 9 of the magazine-arm 2. The forward edges of the sides of the member 22 are spaced rearwardly from the flanges 10 on the arm 2 to form a continuation of the grooves 21 for slidably mounting the staple-driver 25. The bottom transverse portion 23 of the guard member 22 is crowned or shaped to correspond with that of the tabs 20 to conform to the crowned crossbars of the staples as they rest on the tabs.

Referring particularly to the enlarged views, Figs. 4, 6 and 8, it is to be noted that the staple-rest comprising the tabs 20 is offset rearwardly from the forward edges of the side walls 17 of the core 15 to form relatively narrow shoulders 24 disposed below the rest and at the rear of the grooves 21. These shoulders 24 serve as detents or auxiliary rests for supporting each staple as it is fed off from the forward end of the core 15, see Fig. 6, it being noted by reference to Fig. 8 that the transverse portion 23 of the guard 22 is cut back to provide an open space above the shoulders 24. Above the shoulders 24 the sides 9 of the arm 2 are sheared to form extruded portions or lugs 31 which project inwardly therefrom for a purpose explained hereinafter.

The staple-driver 25 is in the form of a hardened metal blade of varying thickness from top to bottom and provided with relatively narrow guiding fins or runners 26 adapted to slide in the grooves 21 at the forward end of the magazine-arm 2. The blade of the driver 25 tapers in thickness from the top toward the bottom throughout its central portion, see Fig. 1, and then is recessed rearwardly at its lower end. The lower recessed end of the driver 25 is thus formed with an offset shoulder 28 raised slightly above its forward edge. Near this end of the driver 25 is a circular hole 27 for connecting it with the staple-applying arm 3. On its rearward face the upper portion of the driver 25 is thickened to provide a substantially rectangular pad or projection 29 having its lower edge in the form of a horizontal shoulder 30 which overhangs the detent-shoulders 24 at the forward end of the core 15. The lower edge of the pad 29, that is the shoulder 30 formed thereby, is straight across the width of the driver, the purpose of this form of construction being to adapt it to engage with and flatten or straighten the crowns of the staples.

The staple-driver 25 is connected to be reciprocated by the arm 3, this connection comprising a stud 33 fastened in the forward end of the arm 3 and having its projecting portion engaging through the hole 27 near the lower end of the driver, see Fig. 1. The staple-applying arm 3 is of inverted channel shape in cross-section with its side walls 34 tapering slightly toward its rearward end which is formed with semicircular ears 35 pivotally connected to the sides of the magazine-arm 2 by means of a crosspin 36, see Figs. 1 and 2. Substantially midway of its length the

arm 3 is widened transversely by offset portions 37 of its side walls 34 while the forepart of the arm narrows again in conformity with its rearward portion. Along its rearward portion the side walls 34 of the arm 3 are joined together by a top wall 38, but forwardly thereof throughout its widened and front portions the top wall is cut away with an extended opening 40 to provide a window or doorway for inserting staples therethrough into the magazine-arm 2. Adjacent the forward end of the arm 3 its side walls are staked or punched to force the metal inwardly in a pair of substantially arcuate portions, shown in Fig. 1, which form abutments 41 adapted to be engaged by the lower edges of the ears or lugs 35 which project from the sides of the arm 2 as shown in Fig. 3, whereof to limit the upward movement of said arm 3 with respect to the arm 2. Suitably secured to the inner faces of the widened portions of the sides 34 of the arm 3, as by welding or riveting, are a pair of studs 45 having reduced central portions bounded by flanges as shown most clearly in Fig. 2. The studs 45 are engaged by the ends of the manually-operative lever 5 in a manner as later explained.

The clinching arm 4 is generally of channel shape in cross-section having its forward longitudinally-tapered portion offset below its main rearward portion, the sides of the latter being of greater depth. At its rearward end the sides of the arm 4 overlap the sides of the magazine-arm 2 and are provided with holes for receiving the cross-pin 36, previously mentioned, to pivotally connect the arm 4 to the arms 2 and 3. Positioned within the forward end of the arm 4 and welded or otherwise suitably secured to the walls thereof is a hardened block 47 formed with clincher-grooves 48 of usual construction, see Figs. 1 and 5, which are in substantial alinement with the lower edge of the staple-driver 25.

The manually-operative lever 5 is of channel shape in cross-section with its rearward portion formed with a rounded bottom wall providing a hand-grip and its forward side walls 49 extended upwardly at an angle to adapt them to straddle the sides of the clincher-arm 4. A crosspin 50, see Fig. 2, projects through holes in the sides of the arm 4 and the side walls of the lever 5 for pivotally mounting the latter on the arm. The upper ends of the side walls 49 terminate in hooks 51 engaging around the studs 45 which project inwardly from the walls of the staple-applying arm 3, see Figs. 1 and 2, whereby to connect the lever 5 for rocking said arm downwardly to reciprocate the driver 25 across the end of the magazine-arm 2. Rearwardly of the hook portions 51 of the lever 5 the sides 49 are formed with cam-faces 52 which operate on the studs 45 with an increased pressure or mechanical advantage, see Fig. 1, during the completion of driving and clinching the staples. The clinching arm 4 is normally maintained in spaced relation to the magazine-arm 2 and the staple-applying arm 3 through the means of a leaf-spring 55 of slightly bowed shape, see Fig. 1. The rearward end of the spring 55 bears on the under side of the magazine-arm 2 and its forward end engages under the crosspin 50 while its central bowed portion bears against the bottom wall of the arm 4. A tongue 56 formed by a portion of the metal slit from the end of the spring 55 is bent upwardly and curved around the top of the pin 50 to connect this end of the spring therewith.

Referring particularly to Fig. 1 of the drawings,

the staples *s* are held from rising up on the core *15* by means of a cover member *60* which overlies their cross-bars and is slideable longitudinally of the magazine *2* to adapt it to open it for receiving the staples inserted through the window or door *40* in the top of the staple-applying arm *3*. The cover *60* may be crowned along its central portion to adapt it to conform to the shape of conventionally-crowned staples and at its rearward end it is bent downwardly to form a tail-piece *61* adapted to be gripped in the fingers to draw the cover rearwardly along the top of the magazine *2*. The cover *60* is maintained in position overlying the upper edges of the sides *9* of the magazine-arm *2* by means of a leaf-spring *63* bearing against the top wall of the staple-applying arm *3*. As shown in Fig. 1 the rearward end of the spring *63* bears against the under side of the top wall *38* of the arm *3*, its middle bowed portion bears against the top of the cover *60*, and its forward end is fastened to the top wall *38* by a lug *64* of the metal slotted therefrom and bent downwardly to project through a hole *65* in the spring.

The staples *s* are advanced along the core *15* in the magazine-arm *2* by means of a staple-pusher *66* of usual construction adapted to overlie and straddle the core. Referring to Figs. 1 and 2, the staple-pusher *66* is constructed of sheet-metal with a top wall *67* and downwardly-bent flanges or side walls *68*. The side walls *68* extend forwardly beyond the forward end of the top wall *67* which is bent downwardly with a portion *69* therebetween as shown most clearly in Figs. 1 and 2. The forward edges of the side walls *68* are adapted to engage the legs of the rearmost staple in the magazine *2* to slide the while series forward on the core *15*. The staple-pusher *66* is slid forwardly along the core *15* under the tension of a helical spring *70*, the forward end of which bears against the bent down portion *69* of its top wall *67*. The rearward end of the spring *70* encloses a hollow stud *71* and bears against its flanged end *72* to press it against the crosspin *36* which pivotally connects the arms *2*, *3* and *4*.

After the cover *60* has been withdrawn along the top of the magazine *2* and the pusher *66* has been retracted therein, the stick *S* of staples is inserted through the opening *40* in the arm *3* and placed in the magazine with the legs of the staples straddling the core *15*. The cover *60* is then slid forwardly on the magazine *2* into the position illustrated in Fig. 1 where its forward end brings up against the guard member *22*. The cover *60* will thus serve to hold the staples from riding up on the core *15* and the implement is ready for operation.

To apply a staple to the work the implement is grasped with the palm of the hand overlying the staple-applying arm *3* and the fingers pressing against the rounded under side of the operating lever *5*. Then by applying pressure to the lever *5* its hooked connection with the studs *45* on the arm *3* will act to swing the latter and the clincher-arm *4* toward each other. During this relative movement between the arm *3* and arm *4* the leaf-spring *55* is compressed, but the spring *63* will resist relative movement between the arm *3* and the magazine-arm *2*. When, however, the forward end of the magazine-arm is brought into contact with the work the arm *3* will continue its motion to compress the spring *63*. The motion of the arm *3* relative to the magazine-arm *2* will cause the staple-driver *25* to be slid down-

wardly in the grooves *21* at the forward end of the magazine-arm. When the magazine is first supplied with staples *s*, that is unless staples already remain therein, the first action of the staple-driver *25* will be to separate a staple *s* from the stick and carry it down onto the detent-shoulders *24*. That is to say, as the driver *25* descends the shoulder *30* on its rearward face will engage the crossbar of the foremost staple *s* in the series on the core *15*, see Figs. 7, 8 and 10, to shear this staple from the strip and carry it down onto the detent-shoulders *24*. During this action of the driver its edge or shoulder *30* will compress the crowned top of the staple *s* to straighten it, thereby causing its opposite legs to be spread apart as shown at *x* in Fig. 10. This compression of the top of the staple will act to spread its legs toward the inner faces of the sides *9* of the arm *2* directly beneath the inwardly-projecting lugs *31* so that the lugs will prevent the staple from rising to any considerable extent above the detent-shoulders *24*.

The staple separated from the strip and moved into reserve position resting on the shoulders *24* beneath the lugs *31* thus will be retained in this position until the driver *25* is raised again by release of the pressure on the lever *5*. As the rearward edge *28* of the driver *25* rises above the shoulders *24*, see Figs. 7 and 8, the staple *s* resting on the shoulders *24* will be pushed off therefrom by the legs of the next succeeding staple on the core *15* as the whole series of staples is advanced by the pusher *66*. At the next descent of the staple-driver *25*, as the implement is again operated, the driver will engage the top of the staple *s* advanced into position beneath its edge *28* to force it down into the grooves *21* and drive it through the work as its legs are bent inwardly by the curved clincher-grooves and clinched on the under side of the work. The purpose of this form of construction and arrangement of the parts is the same as that shown in U. S. Letters Patent No. 2,420,830 granted to Arthur H. Maynard May 20, 1947, the present invention embodying simplification and improvement thereover. The object of this arrangement is to prevent a second staple being driven before the first one has been discharged from the machine or, in other words, to avoid driving one staple on top of another which would be liable to clog the machine. It will be observed that if the driver *25* should be depressed insufficiently to complete the driving and clinching of a staple, a second staple could not be entered into the grooves beneath the driver until the latter has completed the application of the first staple, that is, the staple being driven and remaining in the grooves beneath the driver will prevent another staple being fed off from the detent-shoulders *24*.

The implement may be operated continuously in the manner explained above to apply staples to the work in multiple and usually a fresh supply is inserted in the magazine before all the staples have been exhausted therefrom.

It will be observed from the foregoing specification that the present invention provides an extremely simple and compact form of implement of the plier-type for applying fasteners while operating it in one hand. The structure and arrangement of the parts of the implement are considerably simplified and improved over previously used devices of the same type to render the implement more economical to manufacture without loss of efficiency in its operation.

It is to be understood that while the present improvements are shown as applied to a plier-type of stapling implement they may be adapted for fastener-applying devices of other types and therefore the invention is not limited in respect to its particular use as herein shown. Likewise, various modifications may be made in the structure and arrangement of the parts of the implement without departing from the spirit or scope of the invention. Therefore, without limiting myself in this respect, I claim:

1. A fastener applying implement comprising a magazine for containing a supply of fasteners having crowned crossbars, means to support the fasteners in the magazine, a rest for supporting a fastener below its normal position in the magazine at the forward end thereof to hold it in reserve position, fixed hold-down means engageable across the ends of a fastener on the rest to prevent it from rising up therefrom, a reciprocable driver slideable across the front of the magazine and having a portion engageable with a fastener to carry it down onto the rest, straighten its crowned crossbar and position the ends thereof beneath the hold-down means, and resiliently-operated means for feeding the fasteners forwardly to position the foremost one beneath the driver and cause it to be forced down onto the rest, said feeding means operative thereafter to advance the reserve fastener into position to be driven into the work at a subsequent stroke of the driver.

2. A fastener-applying implement comprising a magazine for containing a supply of U-shaped fasteners having crowned crossbars, a throat at the forward end of the magazine through which the fasteners may be driven to apply them to the work, a core in the magazine for supporting the fasteners in straddled relation thereon, a rest below the top of the core at the forward end of the magazine adapted to support a fastener in reserve position at the rear of the throat, hold-down means projecting across the top of the rest at the sides thereof, a driver reciprocable in the throat of the magazine and formed with a straight edge overlying the rest at the front of the core, means for reciprocating the driver to cause its rearward edge to engage the foremost fastener in the magazine and force it down onto the rest while straightening its crossbar to cause its legs to be separated and the ends of its crossbar carried into position beneath the hold-down means, and means operative to advance the fasteners in the magazine to feed the reserve fastener off from the rest into the throat beneath the bottom of the driver to adapt it to be driven into the work.

3. In a fastener-applying implement, a channel-shaped magazine for containing a supply of fasteners, a throat at the end of the magazine through which the fasteners are driven, means for feeding the fasteners forwardly into the throat, detent-shoulders projecting toward the throat for supporting a fastener carried downwardly thereonto, hold-down means for the fasteners above the detent-shoulders, a driver having a straight rearward edge overlying the detent-shoulders, means for reciprocating the driver to cause its rearward edge to engage the crossbar of a crowned fastener when the driver descends to flatten said crossbar and spread the legs of the staple into position beneath the hold-down means, and means operative to feed the fastener

off from the detent-shoulders when the driver is raised to cause it to be engaged by the bottom edge of the driver to drive it into the work.

4. In a fastener-applying implement, a magazine for containing a supply of fasteners having crowned tops, a core in the magazine adapted to support the fasteners in straddled relation thereacross, detent-shoulders offset below the forward end of the core and adapted to support a fastener in reserve position thereon, hold-down means for the fasteners above the detent-shoulders, a driver slideable across the front of the magazine and having a portion of its rearward face formed with a straight transverse shoulder adapted to engage a fastener advanced beyond the end of the core to carry it down onto the detent-shoulders, said shoulder on the driver acting to straighten the crowned top of a fastener to force its legs outwardly into position beneath the hold-down means, and means operative to feed the fastener off from the detent-shoulders when the driver is raised whereby to advance the fastener beneath the lower edge of the driver to adapt it to be driven into the work.

5. In a fastener-applying implement, a channel-shaped magazine for containing a supply of U-shaped staples having crowned crossbars, a throat at the forward end of the magazine to adapt the staples to be driven therethrough, a core in the magazine for supporting the staples straddled thereacross, detent-shoulders at the forward end of the magazine below the top of the core to adapt them to receive a staple in reserve position, lugs projecting inwardly from the sides of the magazine above the detent-shoulders, a driver reciprocable in the throat of the magazine and having a rearwardly-projecting edge overlying the detent-shoulders at the front of the magazine, means for reciprocating the driver to cause its rearward edge to engage the foremost staple in the magazine to carry it down onto the detent-shoulders while compressing its crossbar to spread its legs into position beneath the lugs on the sides of the magazine, and means operative to advance the staples in the magazine to feed the foremost staple off from the detent-shoulders into position beneath the lower edge of the driver to adapt it to be driven into the work.

6. In a fastener-applying implement, a magazine for containing a supply of U-shaped staples having crowned crossbars, a core in the magazine for supporting the staples in straddled relation thereon, detent-shoulders disposed below and in advance of the forward end of the core to adapt them to support a staple in reserve position thereon, lugs projecting inwardly from the sides of the magazine above the detent-shoulders, a throat in advance of the detent-shoulders through which the staples may be driven, a driver slideable in said throat and having a rearward portion formed with a transverse shoulder overlying the detent-shoulders at the end of the core, means for resiliently feeding the staples forward in the magazine, and means for reciprocating the driver to cause it to first carry a staple down onto the detent-shoulders and flatten its crown to spread its legs toward the sides of the magazine beneath the lugs thereon and to thereafter engage a staple fed off from the detent-shoulders to drive it downwardly in the throat and into the work.

CHARLES M. LINDSTROM.
